Filed May 10, 1939

The diagram shows a rectangular component with a central slot. Four corner features are labeled: 1 is at the top-left, 2 is at the top-right, 3 is at the bottom-left, and 4 is at the bottom-right. The central slot is bounded by a line connecting the midpoints of the top and bottom edges.

INVENTOR

Hugo Leonard Bjorkman

UNITED STATES PATENT OFFICE

2,228,904

WRENCH

Hugo Leonard Bjorkman, St. Albans, N. Y.

Application May 10, 1939, Serial No. 272,753

1 Claim. (Cl. 81—133)

This invention relates to wrenches of the adjustable type, and the primary object thereof is to provide a tool which can be easily and quickly adjusted to different sized nuts.

5 A further object of the invention is to provide a wrench with a pair of adjustable jaws and to arrange the adjusting mechanism in such a way that practically no strain will be exercised on the said adjusting means while the wrench is being used, and thereby insuring a long life and usefulness of such a tool.

10 A further and important object of the invention is to provide a spring release of the adjustment arrangement. Pressing the release spring down and shifting the sliding carriage up or down the handle, will shift the wrench jaws instantly to any desired position.

15 With these and other objects in view, all of which will more fully appear in the following specification of my invention, the same comprises the novel combination, construction, and arrangement of parts hereinafter more fully described and shown in the accompanying drawing and claimed.

20 In the drawing in which,

Fig. 1 is a front elevation of the wrench in accordance with my invention.

25 Fig. 2 is a side elevation with parts broken away showing inner construction thereof, substantially on line 2—2 of Fig. 1.

Fig. 3 is a front elevation of the wrench handle 4 with both jaws and sliding carriage removed to expose construction of same.

30 Fig. 4 represents a perspective view of the adjustable jaw 1.

Fig. 5 is a sectional view through line 5—5 of drawing Fig. 1.

35 Like numerals denote like parts all through the various figures.

40 In carrying out my invention I provide a handle 4, which has a slot 26 near its middle section, teeth 14 are cut on one side of same to allow a gear wheel 6 to move up or down in said slot 26. The upper part or head of the handle 4 has angular inclined slideways to allow jaws 1 and 2 to slide through a sleeve 3 toward or away from each other, depending on up or down movements of the said jaws 1 and 2.

45 The sleeve 3 is provided with guide ribs 15 and 16 to guide the jaws 1 and 2 and grooves 17 and 18 are cut in jaws 1 and 2 to slide on the aforementioned guides of sleeve 3.

The jaws 1 and 2 have channel like grooves 19, 20 at their lower portions to engage guide ribs

24, 25 of the slider member 7. Backplate 10 prevents slider member 7 from coming off handle 4 and is securely connected to slider members 7 and 9 by bolts 11 and 12.

The ratchet wheel 5 and gear 6 having teeth 5 27 and 38, respectively, are rigidly secured together and are rotatably mounted by axle 29 in plates 9 and 10. A spring 8 fastened to slider member plate 10 by a rivet 22 extends through slot 26 of handle 4 and slot 23 of slider member 10 plate 9, a tooth 28 on said spring 8 engaging teeth 27 of ratchet wheel 5.

It can now be plainly understood that by pressing down on spring 8, ratchet wheel 5 is released for action, the whole slideable carriage being 15 movable up or down on wrench handle 4 thereby decreasing or increasing the distance between the faces 33 and 34 of slideable jaws 1 and 2 of the wrench. The upper slider member 7 is guided in its up or down movement in slot 26 of 20 handle 4 by a guide 13 and the lower slider member 9 by guide 21.

It is obvious that the slideable jaws 1 and 2 are always supported and firmly held by sleevebacks 31 and 32 of sleeve 3 and nearly all applied strain 25 in using the wrench is absorbed by these supports.

What I claim is:

In a wrench the combination of a pair of slideable jaws, each jaw having a transverse groove at 30 its lower end, a handle having at one end a pair of angular inclined slideways and a sleeve for the purpose of guiding and supporting the said pair of slideable jaws, said handle having a longitudinally extending slot through the middle section, rack teeth formed on one side of said slot, a carriage slidably mounted on the middle part of the handle, said carriage comprising a longitudinal stem having transverse ribs at one end slideably engaging said grooves and a plate member 40 on each side of said handle secured to said stem, a combination gear and ratchet wheel rotatably connected to the plate members of the carriage, said gear engaging the rack, a spring having a tooth on one side and attached to one 45 plate member of the carriage to detachably engage the ratchet wheel and lock the jaws against spreading movement, guides extending between the plate members of the carriage and attached thereto and through the slot of the handle for 50 the purpose of guiding the slideable carriage in its up or down movement.

HUGO LEONARD BJORKMAN.
